UNITED STATES PATENT OFFICE.

HANS RASMUSSEN, OF CHICAGO, ILLINOIS.

METHOD OF SUPPORTING AND CONSTRUCTING CONCRETE-FLOOR SECTIONS.

1,335,458.

Specification of Letters Patent. Patented Mar. 30, 1920.

Application filed July 18, 1919. Serial No. 311,806.

To all whom it may concern:

Be it known that I, HANS RASMUSSEN, a citizen of the United States, residing at Chicago, in the county of Cook and State of Illinois, have invented certain new and useful Improvements in Methods of Supporting and Constructing Concrete-Floor Sections, of which the following is a description, reference being had to the accompanying drawings, forming a part of this specification, in which corresponding numerals of reference in the different figures indicate like parts.

The object of my invention is to provide a simple and effective method of and apparatus for supporting concrete floors during construction with a view of dispensing with the usual complicated objectionable and expensive shoring heretofore employed for that purpose.

I accomplish said object in the manner hereinafter more particularly described and definitely set forth in the claims:

In the drawings,

Figure 1 is a vertical section taken upon the line 1—1, Fig. 2, viewed in the direction of the arrow there shown, illustrating a section of floor as it would appear in process of construction, with my approved supporting means and false-work,

Fig. 2, is a plan view thereof, and

Fig. 3, is a section corresponding to a part of the left-hand portion of Fig. 1, enlarged to better illustrate the anchoring members and connections.

Referring to the drawings, 1, 1, indicate the usual pillars adapted to support the meeting ends of I-beams or girders 2, which latter, usually, and in the example illustrated, are arranged at right-angles to each other and connected by means of plates 2^a, to serve as supports for ordinary rectangular concrete floor sections. In order to support the forms for receiving the concrete in plastic condition, I provide a plurality of truss-like form-supporting members which consist of I-beams 3, placed horizontally, and having a length corresponding substantially to the width of the floor-section to be formed. Each member 3 is supported at the respective ends by means of vertical supporting members 4, the lower ends of which rest, in turn, upon the girders 2. Brace members 5, are rigidly connected with the girder parts 3 and 4 to hold them securely in place.

55 A form comprising a flat portion made up of a floor 6, corresponding in peripheral

outline to, but somewhat smaller in area than that inclosed by the four girders 2, is secured to, and directly supported by transverse parallel floor joists 7, spaced apart; 60 said joists being located in corresponding vertical planes with the I-beams 3. Reinforcing timbers or bridging joists 8, of somewhat smaller cross-sectional area than that of the floor joists 7, are placed beneath the 65 latter at right angles thereto. Suspending members 9, preferably made of wire loops, are connected at their upper ends by means of swiveled hooks 9^a, with detachable clamps 10, adapted to engage the lowermost flanges 70 upon the I-beams 3. The lower end of each of said loops is arranged to partially encircle the body of an anchor-block 9^b, better shown at the right in Fig. 3, which blocks are preferably formed from cast iron, the 75 body being of substantially cylindrical form with a peripheral shoulder 9^c partially surrounding it, beneath which the loop is passed, thereby serving as an anchorage for 80 said loop. The anchor-blocks 9^b are centrally and longitudinally bored and threaded for the reception of lag-screws 11, which are projected upwardly through bores in the members 8 and 7, respectively, into said anchor-blocks, which latter are placed with 85 their flat lower ends upon the floor 6. Downwardly inclined stirrup members 12, are nailed or otherwise rigidly attached to the ends of the floor-joists 7 and are connected at their lower ends with horizontal supporting members 13. Laging 14 is attached to the inner faces of the members 12 to form a troughlike or girder-box portion arranged to partially inclose each of the four girders 95 2, the bottom of said troughs being also provided with lagging 15, secured to the horizontal members 13. The upper edges of the parts 14 are flush with the upper surface of the floor 6.

In order to support the girder-boxes, I 100 place like anchor-blocks 9^b upon the lagging or bottom 15, above each member 13 and secure them in place by means of like lag-screws 11, passed upwardly through the members 13 and into said blocks. A wire 105 loop 15^a is passed over the top of the girder 2 and beneath the shoulders 9^c of the anchor blocks, of which there are two for each loop, placed beneath and upon opposite sides of the girder. There should be as many 110 loops for each girder as there are cross-bars or members 13 to be supported thereby.

When the form is suspended in the manner indicated, it may be adjusted and leveled by means of the lag screws 11, or by twisting the wire in a well known way.

- 5 When so leveled, the concrete mixture 16, in plastic form, may be poured over the main floor 6 and into the girder boxes, thereby completely enveloping the several girders 2, as clearly shown at the right-hand in Fig. 10 1. The usual metallic reinforcing members or rods 17, are embedded in the concrete. When properly filled and leveled, the mass is allowed to set until sufficiently hard to become self-sustaining, whereupon the forms 15 may be removed and used in like manner in other locations upon the same or other floors.

The form for each square or floor section may be separated from those adjoining by 20 merely removing the members 13 which connect them and support the members 15. When this is done the removal of the several lag-screws 11 permits the entire form of a given section to be lowered.

- 25 The employment of the apparatus described enables the space beneath a given floor to be entirely free from obstruction, while the truss-members 3 and suspending wires 9 do not interfere with the movements 30 of the workmen above.

Having thus described my invention, I claim:

1. The method of constructing concrete floor sections in conjunction with permanent floor-supporting girders, which consists in providing a form adapted to permit the molding of plastic concrete in abutting contact with said girders to constitute a floor-slab in the area between them, placing 35 anchor-blocks in position upon said form to be ultimately and permanently embedded in the concrete structure, detachably projecting screws from beneath through said form into said anchor-blocks, suspending 40 said anchor-blocks to rigid supports held by said girders above the level of the floor-section to be molded, leveling said form while so suspended, filling the same with concrete, allowing said concrete to set and 45 finally removing said form and suspending means.

2. The method of constructing concrete floor sections in operative relation to floor-supporting girders, which consists in providing a form to sustain a floor-section from beneath, locating anchor-blocks upon the upper face of the form in position to be embedded in the concrete, detachably securing 55 said anchor-blocks from beneath the form, mounting truss-members upon said girders above the level of the latter, detachably connecting said truss-members with said anchor-blocks by suspending means to suspend 60 said form in predetermined relation to said girders, filling said form with concrete, 65

allowing the same to set and finally disconnecting said anchor-blocks from said form and from said truss supports respectively.

3. The method of constructing concrete floor sections in operative relation to floor 70 supporting girders, which consists in providing a form having peripheral girder-boxes to sustain a floor-section from beneath and permit the molding of the concrete to embed said girders therein, locating anchor-blocks upon the upper face of the floor of the form and also within said girder boxes in position to be embedded in the concrete, 75 detachably securing said anchor-blocks from beneath the form, mounting truss members 80 upon said girders above the level of the latter, detachably connecting said truss members with the anchor blocks upon the floor of said form by suspending means, connecting the anchor-blocks in said girder 85 boxes with said girders, filling said form and girder boxes with concrete to a predetermined level with respect to said girders allowing the same to set and finally disconnecting said anchor-blocks from said form, 90 and removing said truss supports.

4. The method of constructing concrete floor-slabs between floor girders arranged to inclose a polygonal area, which consists in providing a form having a substantially flat 95 middle portion and marginal trough-like depressions formed to receive, but spaced apart from, said girders, suspending said form at a predetermined height with respect to that of said girders by means of superimposed 100 trusses having suspending members in operative connection with anchor blocks detachably connected from beneath to the upper face of said forms on said middle portion, said trusses being arranged to 105 bridge the space between while supported upon said girders, adjusting the height and level of said form, filling said form with plastic concrete, allowing the same to set and finally removing said form and suspending 110 members.

5. The combination with horizontally disposed girders arranged to inclose a polygonal space, of a form having a substantially flat horizontal middle portion and marginal 115 trough-like depressions formed to partially inclose but spaced apart from said girders, superimposed trusses removably mounted upon and arranged to bridge the space between parallel girders, suspending members 120 secured to said trusses, anchor-blocks upon said form secured to said suspending members and screws extending upwardly from beneath said form and threaded into said anchor-blocks.

6. An apparatus for forming concrete floor-sections in conjunction with floor-supporting girders, comprising in combination, a plurality of removable trusses having their ends mounted upon and supported by said 125

girders, suspending means depending from said trusses, a form for molding a concrete slab between and in contact with said floor-girders, anchor blocks upon said form in operative connection with said suspending means, anchor-blocks and independent screw adjusting means in operative connection with each of said anchor-blocks for separately adjusting the height of the several portions of said form.

7. An apparatus for forming concrete floor sections in conjunction with floor-supporting girders, comprising, in combination, a plurality of removable superimposed trusses arranged to bridge the space between parallel girders, a plurality of vertical sus-

pending members depending from each of said trusses, a form for molding a concrete slab between and in conjunction with said girders, anchor-blocks upon said form in operative connection with said suspending members and lag-screws projected from beneath through said form into said anchor-blocks.

In testimony whereof I have signed this specification in the presence of two subscribing witnesses, this 12th day of July, 1919.

HANS RASMUSSEN.
